ATTORNEY

UNITED STATES PATENT OFFICE.

SAMUEL C. McKEOWN, OF EAST ORANGE, NEW JERSEY, ASSIGNOR TO SPLITDORF ELECTRICAL COMPANY, OF NEWARK, NEW JERSEY.

BRUSH-HOLDER.

1,311,904.

Specification of Letters Patent.

Patented Aug. 5, 1919.

Application filed September 25, 1917. Serial No. 193,119.

To all whom it may concern:

Be it known that I, SAMUEL C. McKEOWN, a citizen of the United States, and resident of East Orange, in the county of Essex and State of New Jersey, have invented certain new and useful Improvements in Brush-Holders, of which the following is a specification.

My invention relates to brush holders for electrical apparatus used in connection with ignition systems for internal combustion engines.

My invention is particularly adapted for use in connection with a magneto used for the purpose of producing and distributing sparking current to the sparking devices located in the various engine cylinders. Magnetos used for this purpose usually have a distributor block which carries the contacts to which the spark plug wires are attached; at the same time the block acts as a housing for the distributing finger which serves as a medium for conducting current from the secondary of the high tension coil to the various distributor points by way of a distributor brush carried by the distributing disk or finger.

In order that the brush carried by the rotating distributing finger may be kept in its proper working position a spring of some kind is utilized to continually force the brush outward from its retainer and when the block is removed for any purpose whatsoever, the distributor brush will pop out of its retainer unless restrained by some means.

One of the objects of my invention is to provide a brush holder which has a restraining means suitable for retaining the brush in the holder when the distributor block has been removed.

Another object of my invention is to provide a retainer which will serve as a means for withdrawing the brush from the holder itself whereby damage to the brush and its operating spring is reduced to a minimum. That is to say, the retainer acts as a protector for the brush and spring.

These and other objects will be apparent to one skilled in the art after a study of this specification in connection with the drawing, in which Figure 1 is a fragmentary sectional view of a portion of a distributor block with the distributing finger and means for driving the same.

Fig. 2 shows one form of my brush holder set into the distributing finger but with the retainer nearly withdrawn from the holder.

Fig. 3 is a modified form of brush holder and retainer with the retainer partly withdrawn from the holder.

Fig. 4 is a sectional view of Fig. 2 along the line 4—4, but with the retainer farther in the holder.

Fig. 5 is another form of brush retainer which may be used for the retainer shown in Fig. 2.

Fig. 6 is another way of holding the brush in the retainer.

Referring now particularly to the details, 1 is a portion of the end plate of a magneto 70 within which is mounted a ball bearing 2 that carries a distributor gear 3. Gear 3 is driven in the usual way from the pinion on the armature or rotor of the magneto but since this is all old and well understood and 75 forms no part of my invention further description of this part of the magneto does not appear necessary. The sleeve 4 to which the gear 3 is attached carries an insulating finger 5 having a stem 6 in which is molded 80 a metal insert 7, which carries a brush 8 for the purpose of collecting the high tension current from any suitable connecting device. Preferably molded integrally with the finger 5 is a brush holder 9 adapted to 85 carry a retainer 10, which in the forms shown in Figs. 2 and 4 is U-shaped. The retainer 10 is indented along one side at 11 which indentation serves as a guide for the brush 12 which has a groove 13 to coact 90 with the guide 11. The brush holder 9 also has an indentation 14 that matches with indentation 11 of the retainer so that the retainer 10 is guided in the brush holder 9.

Attached to the bottom of the brush 12, in 95 any suitable manner such as plate 15 which may be soldered to the brush 12, is a rod 16 having a head 17 placed thereon after the rod 16 has been passed through the hole in the bottom of the retainer 10. A spring 18 100 is supported by the rod 16 between the bottom of the retainer and the bottom of the brush 12 and serves to push the brush outward to hold it in its normal working position, which, as shown in Fig. 1, is against 105 the pathway of the distributor block 19 in which are molded a number of inserts 20 corresponding to the number of engine cyl-

inders required to be served by the mag-
neto. The wires running from the dis-
tributer block 19 to the engine cylinders are
connected to the contacts 20 by means of
5 the openings 21 and screws passing through
the threaded holes 22. The distributer
block 19, as shown, has other contact points
23 but since these form no part of my pres-
ent invention they are not further described
10 herein.

It will be seen by reference to Fig. 2 that
when the retainer 10 and brush 12 are in
their normal working position the head 17
of bolt 16 passes through a hole 24 in the
15 bottom of brush holder 9 and the insulated
part of the finger 5. When the distributer
block 19 is removed from the magneto the
brush 12 will move outwardly in the retainer
10 only so far as the head 17 on the bolt 16
20 will permit it and in order to withdraw the
brush instead of pulling directly thereon the
retainer 10 is seized and retainer and brush
together are withdrawn from the holder 9.
The modification shown in Fig. 5 illustrates
25 a complete box type of holder for the brush.
One of the side walls is slit at 25 in order
that the retainer 26 may expand enough to
frictionally engage the side of the holder 9
30 to keep the retainer 26 frictionally in place
therein in the same manner that the retainer
is held in place as will be seen by its po-
sition in Fig. 2 wherein the arms are so
formed as to have a certain outward ten-
35 sion whereby when the retainer 10 is in its
normal working position in the holder 9 it
will grip the side walls of the holder.

In the modified form shown in Fig. 3 one
side of the retainer has a hook 27 formed
thereon and this side has a slight set at 28
40 so that when the retainer is withdrawn from
the holder the hook 27 will spring outward
as shown in Fig. 3 whereby the brush 12
may be readily withdrawn from the re-
tainer. In this modified form the brush,
45 retainer and holder have grooves and guide-
ways corresponding to the form shown in
Fig. 2 but a different type of spring attach-
ment is used for the movement of the brush.

In Fig. 6 the brush 12 has a hole 29
50 through it and the rod 16 extends through
a longitudinal hole that enters the cross-
hole 29, and is upset at 30 so it will not pull
out of the longitudinal hole. This makes
a very cheap and quick attachment of the
55 brush to the retainer.

While I have shown certain forms of my
invention it will be apparent that numerous
changes and alterations may be made in the
various details without departing from the
60 spirit of my invention or the scope of the
appended claims.

Having thus described my invention what
I claim is:—

1. In a device of the class described, a
brush having a channel therein, a retainer 65
for the brush having a guide adapted to co-
operate with said channel, a holder for the
retainer, a spring mounted within the re-
tainer for moving the brush outward to take
up wear, and means associated with the 70
brush and retainer for limiting the outward
movement of the brush as described.

2. In a device of the class described, a
brush having a channel therein, a retainer
75 for the brush having a guide adapted to co-
operate with said channel, a holder for the
retainer having a guide adapted to coöper-
ate with the guide in the retainer, a spring
mounted within the retainer for moving the
80 brush outwardly to compensate for wear,
and means coöperating between the brush
and retainer for limiting the outward move-
ment of the brush for the purpose described.

3. In a device of the class described, a
brush having a channel therein, a retainer 85
for the brush having a guide adapted to co-
operate with said channel, a holder for the
retainer, a pin attached to said brush and
passing through the bottom of the retainer
and having a head thereon, a spring sup-
90 ported by said pin and acting between the
brush and retainer to move the brush out-
wardly to compensate for wear, said head on
the pin serving to limit the outward move-
ment of the brush and a clearance hole 95
through and below the holder for the move-
ment of said pin and head thereon.

4. In a distributing device of the class de-
scribed, a block of insulating material, a
brush holder molded permanently therein, 100
a resilient brush retainer adapted to fric-
tionally fit within said holder, a brush mov-
ably mounted within said retainer, a spring
to move the brush outwardly as the same
wears, and means associated with said brush 105
and retainer for limiting the outward move-
ment of the brush.

5. In a distributing device of the class
described, a block of insulating material, a
brush holder molded permanently therein, a 110
resilient brush retainer adapted to friction-
ally fit within said holder, a brush movably
mounted within said retainer, a spring to
move the brush outwardly as the same wears,
and means associated with said brush and 115
retainer for limiting the outward movement
of the brush, said retainer serving as a
means for withdrawing the brush from the
holder whereby damage to brush and spring
is reduced to a minimum.

In witness whereof I affix my signature.
SAMUEL C. McKEOWN.
